MATTRESS OR CUSHION AND SPRING UNIT
THEREFORDavid T. Owen and Charles Dietrich, Cleveland,
Ohio, assignors to The Owen Automatic Spring
Machinery Company, a corporation of Ohio

Application June 5, 1930, Serial No. 459,377

4 Claims. (Cl. 5—267)

Our invention relates to improvements in mattresses and cushions of the type having a spring unit therein.

An object of the invention is to provide an improved spring construction of the type comprising a plurality of coil springs permanently connected to form a spring unit.

Heretofore, it has been customary to provide such spring units with rim wires defining the margins of the unit. The unit is thus stiffened against flexure in the plane of the unit and must be made closely to size, to fit the particular fabric envelope in which it is to be inserted. The envelopes are made of different sizes and particularly in the case of cushions for seats and chairs many different sizes must be provided which may vary by a small amount one from another. As a result, operators who place the spring units in the envelopes frequently crowd 20 into an envelope a unit that is a size too large therefor, with the result that the unit buckles and provides an uneven cushion surface.

It is an object of our invention to overcome this difficulty by providing a spring unit which 25 is flexible in the plane of the unit, so that buckling will not result if the unit is placed in an envelope of smaller dimensions than the normal dimensions of said unit.

Another object of the invention is to provide 30 a spring unit formed with a resiliently flexible border portion on one or more sides thereof adapted to keep an envelope or cover under tension and thereby overcome wrinkling of the cover.

In a specific form of our invention we provide 35 a spring unit in which the rim wires are entirely dispensed with and the unit is bordered by coil springs which are individually laterally compressible. An advantage of this construction is 40 that the units do not have to be made in as many sizes as has heretofore been necessary, because the unit may be compressed to a considerable extent in width or length or both, to fit different sizes of envelopes.

Another object of the invention is to provide 45 a spring unit in which the coil springs are clipped to connecting wires, but the wires lie within and not exterior to the unit.

Other objects and advantages will appear in 50 the following description of an embodiment of our invention and a modification thereof and thereafter the novelty and scope of the invention will be pointed out in the claims.

In the accompanying drawing:

Figure 1 is a plan view of a spring cushion

with the envelope partly torn away to show our spring unit;

Fig. 2 is a view in section taken on the line 2—2 of Fig. 1;

Fig. 3 is a detail view in perspective of the 6 means for clipping two spring coils to a connecting wire;

Fig. 4 is a view in section taken on the line 4—4 of Fig. 3; and

Fig. 5 is a fragmental plan view of a modified 65 form of spring unit.

In the drawing, we show a plurality of open-end coil springs 10. By "open-end", we mean that the extremities of each spring are not affixed to another part of the same spring. The 70 springs are preferably of the hour glass shape, but while the shape is preferred for reasons which will be given hereinafter, our invention is not limited to the use of hour-glass springs.

As shown in Fig. 1, the springs are arranged 75 in horizontal rows A and B with a tie wire 11 between each pair of rows to which the adjacent upper end coils of the springs are clipped. Similar tie wires 12 are provided to which the lower end coils of the springs are clipped. We prefer 80 to use the type of clip shown in Figs. 3 and 4, wherein each clip consists of a strip of metal 13 which is wrapped about adjacent portions of two springs 10 and an intervening tie wire 11 or 12, as the case may be. The clip is then 85 indented, as indicated at 14, such indentation extending into and fixing the clip rigidly to the connecting wire and one of the spring portions embraced by the clip. However, the other spring portion is free to turn in the clip. Thus, each 90 connecting wire has hinged connection with the row of springs on one side thereof and fixed connection to the row of springs on the other side.

It is to be noted that the springs of each row 95 are not directly connected to one another, but are held in mutually spaced relation by the tie wires 11 and 12. The end coils of the springs in the rows A are each connected to said wires at two diametrically opposite points, but those in the two outer rows B are left free at their outer sides to serve as cushioning margins for opposite sides of the spring unit. Similar cushioning margins for the opposite ends of the unit are provided by two transverse rows of springs C which are clipped 100 at the top and bottom to the end coils of the rows A, with a transverse tie wire 15 intervening therebetween. The tie wires 15 serve not only to maintain the springs of rows C in mutually spaced relation but also tie the rows A together. Each corner

of the spring unit is filled by an individual coil spring D whose end coils are clipped to adjacent coils of the rows B and C. Preferably clips of the type shown in Figs. 3 and 4 are used throughout the spring unit and in order to preserve uniformity of spacing, short pieces of wire 16 are interposed between the spring parts in the clips that connect the springs D to the rest of the unit.

Preferably, the marginal springs are also of the open end type and are connected to the tie wires at their free flexible extremities. The only exceptions being the corner springs D which are connected to two adjacent springs in rows B and C respectively.

The spring unit thus formed is inserted in an envelope 18 lined with suitable padding 19. If desired, the padding may bear directly on the springs without any intermediate fabric lining, and also if so desired the padding may be omitted from the underside of the cushion, as in Fig. 2. Preferably, the normal unsprung width of the spring unit is wider than the envelope so that when the unit is inserted in the envelope the marginal rows of springs will be compressed as illustrated in Fig. 1. This will place the envelope under tension, holding the top of the envelope smooth and taut. Since the springs in the marginal rows are individually attached to the unit at one side only they are capable of being compressed laterally to a considerable extent without buckling the unit, so as to fit into envelopes varying considerably in both width, and length and the individual marginal springs will take up any local unevennesses in the cushion. Preferably the marginal springs should not be compressed to such an extent that their coils will clash against coils of springs in the rows A. If hour-glass springs are used there will be no danger of clashing even when the marginal springs are greatly compressed laterally, and for this reason hour-glass springs are preferable to cylindrical springs.

Obviously, it is not necessary to provide cushioning margins on all four sides of the unit. Such margins may be provided only on one side, or on one side and one end, or in any other combination desired. As long as one of the margins is resiliently flexible it may be used to keep the envelope taut. The other margins will then be defined by outer tie-wires which will serve as rim wires. Such a construction is indicated in Fig. 5, wherein the tie wire 15 is shown at the outer margin of the unit and there is no cushioning row connected to said wire 15, so that the latter then serves as a rim wire.

Having thus described our invention what we

claim as new and desire to protect by Letters Patent is as follows:

1. A spring unit for a mattress or cushion, comprising a plurality of rows of coil springs, tie-wires intervening between said rows, means permanently connecting each tie-wire to the springs adjacent thereto, transverse tie-wires, and means permanently connecting adjacent end springs of successive rows thereto, the springs in certain marginal rows of the unit being free at their outer side and individually compressible in the plane of the unit. 80

2. A spring unit for a mattress or cushion, comprising a plurality of rows of spaced coil springs, tie-wires intervening between the rows, a clip connecting each tie-wire to the springs on opposite sides thereof, each clip being fixed to the tie-wire and a spring on one side thereof and providing hinged connection with the spring on the other side of the wire, and transverse tie-wires clipped to the end springs of all the rows except the outer rows, the springs of the latter rows being free at their outer side. 90

3. A spring unit for a mattress or cushion, comprising a plurality of rows of spaced coil springs, tie-wires intervening between the rows, a clip connecting each tie-wire to the springs on opposite sides thereof, each clip being fixed to the tie-wire and a spring on one side thereof and providing hinged connection with the spring on the other side of the wire, transverse tie-wires clipped to the end springs of all the rows except the outer rows, and a transverse row of springs clipped to one of the transverse wires, the springs of said outer two rows and of said transverse row being free at their outer side. 105

4. A spring unit for a mattress or cushion, comprising a plurality of rows of spaced coil springs, longitudinal tie-wires intervening between the rows, a clip connecting each tie-wire to the springs on opposite sides thereof, each clip being fixed to the tie-wire and a spring on one side thereof and providing hinged connection with the spring on the other side of the wire, transverse tie-wires clipped to the end springs of all the rows except the two outer longitudinal rows, a transverse row of springs clipped to one of the transverse wires, the springs of said outer two rows and of said transverse row being free at their outer side, and a corner spring at each end of the transverse row, each corner spring being clipped to the adjacent end springs of an outer longitudinal row and the transverse row. 110
